Primary Examiner—Joel Sincavage**Attorney, Agent, or Firm—Oldham & Oldham Co., L.P.A.****[57] CLAIM**

The ornamental design for a electric plug retainer, as shown and described.

DESCRIPTION

FIG. 1 is a perspective view of the invention in an installed status;

FIG. 2 is an exploded perspective view of the invention in an unassembled status showing the relationship of the parts, one to the other, a receptacle plate, a retainer clip, a plug cover, and a plurality of wire ties;

FIG. 3 is a front elevation view of the receptacle plate;

FIG. 4 is a rear elevation view of the receptacle plate;

FIG. 5 is a top plan view of the receptacle plate;

FIG. 6 is a bottom plan view of the receptacle plate;

FIG. 7 is a side elevational view of the receptacle plate, the opposite side being a mirror image;

FIG. 8 is a front plan view of the retainer clip;

FIG. 9 is a rear elevation of the retainer clip;

FIG. 10 is a top plan view of the retainer clip, the bottom plan view being a mirror image;

FIG. 11 is a side elevational view of the retainer clip, the opposite side being a mirror image;

FIG. 12 is a rear elevational view of the plug cover;

FIG. 13 is a front elevational view of the plug cover;

FIG. 14 is a top plan view of the plug cover;

FIG. 15 is a left hand end elevation view of the plug cover; and,

FIG. 16 is a right hand elevation view of the plug cover. In FIGS. 3-16, the complete assembly of parts has been omitted for convenience of illustration.
